UNITED STATES PATENT OFFICE.

BARTON H. HICKOK AND FREDERICK C. HICKOK, OF ELDON, MISSOURI.

TRUSS.

1,160,408.

Specification of Letters Patent. Patented Nov. 16, 1915.

Application filed June 11, 1915. Serial No. 33,449.

To all whom it may concern:

Be it known that we, BARTON H. HICKOK and FREDERICK C. HICKOK, citizens of the United States, residing at Eldon, in the county of Miller, and State of Missouri, have invented certain new and useful Improvements in Trusses, and do hereby declare that the following is a full, clear, and exact description of the same, reference being had to the annexed drawings, making a part of this specification, and to the letters and figures of reference marked thereon.

The object of our invention, generally stated, is to provide a truss having characteristics of frame structure and pad which render it light, capable of easy and certain adjustment while on the body without the disconnection, or separation of any parts and capable of automatically conforming to the bending movements of the body.

Other objects and advantages will appear when the nature of the invention is herein-after set forth more in detail.

In the accompanying drawings—Figure 1 is a perspective view of a truss embodying our invention; Fig. 2 is a vertical section through one of the pads.

Our truss frame is composed of a pair of similar rods or bars 10 that are slidably connected by an eye or loop 11 on one end of each through which the other rod passes, the eye 11 of one dipping or inclining down and the eye of the other inclining up, so that the portions of the two rods between the two eyes are placed one above the other, and virtually parallel. The obliquity, or inclination of the eyes is such that the portion of the rod within an eye is pinched or clamped with sufficient pressure to prevent slipping of the rod accidentally, while permitting intentional longitudinal movement in either direction by a pull of the hands, for the purpose of shortening or lengthening the frame to suit the size of the body, or to vary the pressure of the pads at the desired point. The rods or bars are made of flexible spring metal to facilitate both the sliding action when required and the clamping action of the eyes.

The frame-forming wires are bent on a simple curve from the outer ends forward, so as readily to conform to the form of the body, and they will bend or flex when applied to the body, but while at all times maintaining the desired pressure upon the pads.

Upon the upper bar or rod 10, we pivotally mount preferably two pads 13, each pad having on its outer side a pivoting loop 14 through which the rod passes, said loop being placed below the vertical center of the pad (which is preferably oblong) so that the pad reaches well up on the wall of the abdomen,—a desirable thing in the case of a corpulent person in that any danger is avoided of the intestines resting upon the top of the pad.

Another very important advantage of this eccentric pivoting of the pad is that the portion above the pivot becomes an effective lever of good length so that by the pressure of the body outwardly upon it, as in stooping, the lower portion which is situated over the rupture is pressed inward, thus exerting an inward closing pressure under conditions which make it highly desirable. We pivot the pads upon the upper wire so that as they are located at the inner sides of both wires, the lower wire will act as a stop to limit the outward swing of the pads at their lower ends in consequence of their unbalanced condition and thus serve to maintain the pads in substantially a vertical condition and thereby facilitating, or rendering more convenient the application of the truss to the body. Besides the pivotal motion upon the upper frame rod 10, backward and forward, we provide for an oscillating movement sidewise by pivotally connecting the loop 14 to the pad on a horizontal axis at right angles to the axis which the frame rod constitutes, so that in reality each pad is supported by a universal joint that allows any desired adjustment of the position of the pad, and hence, the pad can have the flat form shown and does not require any spherically curved, or other convexly rounded configuration on the body-engaging side.

Each pad is preferably made of a sheet metal plate 15, to which is secured a soft body 16, preferably of sponge rubber, which is on the body-engaging side of the pad. Besides the swinging adjustment of the pads that are possible, each pad is shiftable lengthwise of the frame, and a simple and efficient means for fixing its position consists of a pair of rings, or collars 17, one on either side of the pad pivoting loop 14, which rings, or collars are shiftable along the upper rod 10 and being made of rubber, or some other friction producing material

remain at the points to which they are shifted without the necessity of employing any holding device, while being readily shiftable under proper pressure of the fingers.

At the outer end each frame rod has an eye or loop 19 for engagement by a hook 20^a on a light elastic band or strap 20 which goes around the back portion of the body to secure the pad-carrying frame thereto. The elastic band, or strap 20 is adjustable as to length by means of a buckle 21 which may be of well-known construction. Said frame is designed to extend only across the front of the body, on a line with the rupture. As will be evident, adjustment of the frame lengthwise can be easily and quickly done without removing the appliance from the body, for merely a sliding movement of one rod 10 along the other is required.

Having thus described our invention what we claim is—

1. A truss comprising a frame formed of rods, each rod having an eye through which the other rod passes and through which it is slidable to vary the length of the frame, each eye being integral with its rod and extending obliquely of the rod which passes

through it to exert a clamping effect and a pad mounted upon said frame.

2. A truss comprising a frame formed of rods, each rod having an eye through which the other rod passes and through which it is slidable to vary the length of the frame, and a pad eccentrically supported upon one of said rods below the vertical center of the pad, said supporting rod being arranged above the other rod.

3. A truss comprising a frame formed of rods, each rod having an eye through which the other rod is slidable to vary the length of the frame each eye being integral with its rod and extending obliquely of the rod which passes through it to exert a clamping effect; a pad supported by said frame, and a band extending between the outer ends of said rods, the outer ends of said rods being formed into eyes for the attachment of said bands.

In testimony whereof we affix our signatures in presence of two witnesses.

BARTON H. HICKOK.
FREDERICK C. HICKOK.
